[57] CLAIM

The ornamental design for the electrical connector, as shown and described.

DESCRIPTION

FIG. 1 is a top plan view of an electrical connector showing our new design, the electric cord being shown broken away to depict indeterminate length;

FIG. 2 is a front elevational view thereof;

FIG. 3 is a side elevational view thereof, the opposite side being a mirror image;

FIG. 4 is a rear elevational view thereof; and

FIG. 5 is a bottom plan view thereof.
